UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR-DOOR-OPERATING MECHANISM.

Application filed December 27, 1921, Serial No. 525,105.

To all whom it may concern:

Be it known that I, ARGYLE CAMPBELL, a citizen of the United States, residing at Chicago, in the county of Cook and State of Illinois, have invented a certain new and useful Improvement in Car-Door-Operating Mechanism, of which the following is a full, clear, concise, and exact description, reference being had to the accompanying drawings, forming a part of this specification.

This invention relates to improvements in car door operating mechanism.

In certain types of dump cars, it is customary to employ deep-bellied side sills or girders, thus making it exceedingly difficult to employ any of the usual types of door mechanism satisfactorily on account of the inaccessibility of the parts.

One object of my invention is to provide a simple and efficient door lifting and locking arrangement for dump cars which is especially adapted for those types of cars having deep side sills and pivoted floor doors between the sills and wherein the mechanism must necessarily be operated at the side of the car.

Another object of my invention is to provide a safety device for door operating mechanisms, which safety device is automatically operable to prevent damage to the parts when the doors are suddenly released under load, which damage might otherwise occur by reason of carelessness or ignorance of the operator in releasing the doors.

In the drawings forming a part of this specification, Figure 1 is a vertical, longitudinal, sectional view of a portion of a dump car showing my improvements in connection therewith, the section being taken in a plane inside of the side wall and side sill of the car and looking toward the center sill of the car. Figure 2 is a top plan view of the construction shown in Figure 1 but with the fixed floor boards omitted and the doors indicated conventionally by dotted lines, in order to better illustrate the door operating mechanism and its relation to the parts of the car underframe. Figure 3 is a

proved safety device in connection therewith. In this figure, the parts are shown in the position assumed when the shaft is locked. Figure 5 is a view similar to Figure 4 but illustrating the position assumed by the parts when the shaft is released and the safety feature operative. And Figure 6 is a vertical, sectional view of the side sill of the car taken at the right of Figure 4 and showing the structure illustrated in Figure 4, in edge elevation.

In said drawings, the car is shown as provided with a deep-bellied side sill 10, built-up center sill 11, side wall 12, and pressed diaphragms or needle beams 13, 14, 15 and 16. In the particular type of car shown, eight pivoted floor doors would be employed, four on each side of the center sill, the four doors on one side being arranged in pairs separated by fixed floor sections. Only one pair of such doors is illustrated in the drawings, it being understood that there will be a corresponding pair transversely aligned therewith but on the opposite side of the center sill and that the operating mechanism which I have shown, is adapted for simultaneously operating four doors. The fixed floor sections are indicated at 17, 18 and 19, the fixed floor section 18 being intermediate the two pivoted doors 20 and 21, shown in the drawings. The floor section 18 bridges the space between the two relatively shallow needle beams 14 and 15, thus affording a suitable cover and protection for the operating shaft and other parts of the mechanism associated therewith. The door 21 is pivotally supported by suitable brackets 22 secured to the deep needle beam 13 and the door 20 is similarly supported by brackets 22 secured to the shallow needle beam 16. It will be noted that the doors 20 and 21 are adapted to swing about axes extending transversely of the car and that the free edges of the doors are extended toward each other and engage under floor plates 23—23 secured to the edges of the fixed floor section 18.

In carrying out my invention, I employ a vertical, transverse, sectional view of the transversely extending operating shaft 24 structure illustrated in Figures 1 and 2 and which is mounted in suitable bearings carried by the side sill 10 and center sill 11, it corresponding substantially to the broken section line 3—3 of Figure 2. Figure 4 is an end elevational view, upon an enlarged scale, of the means for locking and releasing the door operating shaft and showing my im-

proved safety device in connection therewith. In this figure, the parts are shown in the position assumed when the shaft is locked. Figure 5 is a view similar to Figure 4 but illustrating the position assumed by the parts when the shaft is released and the safety feature operative. And Figure 6 is a vertical, sectional view of the side sill of the car taken at the right of Figure 4 and showing the structure illustrated in Figure 4, in edge elevation.

square or other non-circular end 25 by which it may be rotated by means of a claw bar or other suitable tool. For each pair of doors 20 and 21, the shaft is provided with a pair 5 of chain or cable winding drums 26-26, the drums being rigidly secured to the shaft. Each of said drums is provided with right and left helical grooves 27 to accommodate the oppositely extending cables or chains 10 indicated conventionally at 28-28 in Figure 1.

Each chain or cable 28 extends over a sheave wheel 29 rotatably supported on a heavy pivot pin 30 mounted in a pair of 15 flanges 31-31 formed integral with a bracket 32 secured to a needle beam 14. As clearly shown in Figure 3, the flanges 31 of each bracket 32 are curved and flared toward the winding drum so as to facilitate 20 the passage of the chain or cable through the bracket. Opposite each sheave wheel 29, the bracket is formed with a vertically elongated opening 33 which alines with a corresponding opening 34, cut in the web 25 of the needle beam. It will be noted that the securing flanges of the brackets 32 reinforce the needle beams around the openings thereof and thus compensate for the metal removed.

30 The ends of the chains or cables 28 are attached to eye-bolts 35 which are horizontally adjustably mounted in anchor castings 36 secured in line therewith to the under sides of the doors. Each of said anchor castings 35 36 is provided with a bell mouth 37 through which the cable or chain passes.

By rotating the shaft in a clockwise direction, as viewed in Figure 4, the chains or cables from all four doors will be simultaneously and uniformly wound around the respective drums, thus elevating the doors to closed position. The doors will be held in closed position so long as the operating shaft is prevented against rotation in a 40 counter-clockwise direction. As hereinbefore noted, the floor section 18 covers and protects the shaft, drums, flexible connections and also the sheave wheels 29 and brackets are amply protected against injury 45 during discharge of the load.

50 To lock the operating shaft, the latter has secured thereto outside of the side sill 10, a ratchet wheel 38, as best shown in Figures 4 and 5. The bearing for this end of the 55 shaft is formed on a reinforcing casting 40 which is secured to the inner side of the side sill 10, as shown by full lines in Figure 6 and by dotted lines in Figure 4. Cooperable with the ratchet wheel 38 is a latch lever 60 designated generally by the reference A. Said lever A is pivoted at its upper end on the pivot bolt 41, said bolt 41 being carried at its inner end by said plate 40 and at its outer end by an outer cover plate 42 which 65 is held spaced from the side sill 10. Near

its point of pivotal support, the latch lever A is formed with a pawl shoulder 43 adapted to engage with the teeth of the ratchet wheel 38 in such a manner as to prevent the latter from rotating counter-clockwise as 70 shown in Figure 4. At its lower end, the lever A is formed with a suitable handle 44 and intermediate said handle 44 and the pawl shoulder 43, the side of the lever A adjacent the ratchet wheel 38 is provided 75 with a lower curved shoulder 45 and above the latter with an inclined guiding face 46. The cover plate 42 is also so shaped on its edge farthest from the ratchet wheel 38, as indicated at 47, as to provide a pocket or recess, in conjunction with the adjacent edge of the lever A, for a cylindrical arm 48, as best shown in Figure 4. The arm constitutes an integral lateral extension from a lever 49 which is pivotally supported as indicated at 50 between the plate 42 and the side sill of the car, it being noted that the point of pivotal support 50 is below and to one side of the normal position of the arm 48 as shown in Figure 4.

90 The lever A is held in locked relation with the ratchet wheel 38 by a cam plate 51 pivotally supported as indicated at 52 between the cover plate 42 and the side sill 10. Said cam plate 51 cooperates with a curved cam 85 surface 53 formed on the upper end of the lever A.

95 As is well known to those skilled in the art, when pivoted dump doors of a car are released under load, the doors fall very rapidly and immediately begin to spin the operating shaft and parts movable therewith. In releasing such an operating shaft having a ratchet wheel, it frequently happens that the operator becomes careless or, 100 through ignorance, allows the locking dog or pawl to fall back into engagement with the ratchet wheel when the latter is spinning, with the result that the parts are frequently 105 broken or jammed. To automatically eliminate damage arising from the causes mentioned, I have provided the peculiar shaped latch lever A and the detent lever 49. By referring to Figure 5, it will be seen that, 110 when the lever A is shifted to its release 115 position A', the detent lever 49 automatically falls under the influence of gravity to the position shown at 49' in Figure 5 where the arm 48 thereof engages against the curved shoulder 45 of the lever A, thus positively 120 holding the lever in its inoperative position and preventing the pawl shoulder 43 thereof from accidentally swinging back into engagement with the ratchet wheel 38. To prevent the detent lever 49 from swinging 125 downwardly past the shoulder 45, the plate 42 is formed with the shoulder 54 which engages the detent lever 49 and limits it in its downward swinging to the position 130 shown in Figure 5. The arm 48 of the de-

tent lever is considerably extended as best shown in Figure 6 so that it may be easily grasped and lifted upwardly and forced home to its normal position shown in Figure 4 where it will be noted the same is locked by means of the plate 42 and lever A, when the latter is in turn locked by the cam plate 51. During the winding up of the mechanism, it is of course desirable that the pawl shoulder 43 keep dropping into place automatically against the teeth of the ratchet wheel as the latter is rotated clockwise. To this end, the detent lever and latch lever A are so positioned and weighted that the latch lever A may be swung outwardly sufficiently to clear the teeth of the ratchet wheel 38 when the latter is being rotated clockwise without, however, the detent lever pushing the latch lever A to the full release position shown in Figure 5.

The safety arrangement shown and described consists of few parts all of which may be manufactured at comparatively small expense in the form of castings and efficiently performs the desired function.

I have herein shown and described what I now consider the preferred manner of carrying out the invention but the same is merely illustrative and I contemplate all changes and modifications that come within the scope of the claims appended hereto.

I claim:

1. The combination with a shaft having a latch wheel thereon; of a latch co-operable with said wheel; a detent movable under the force of gravity to a position to retain said latch in inoperative position with reference to said wheel; and means on said latch, movable therewith, engaging said detent for rendering the latter ineffective when the latch is in operative relation to said latch wheel, and controlling the movement thereof under the influence of gravity to permit the same to move into retaining position upon disengagement of said latch from said latch wheel.

2. The combination with a shaft having a latch wheel; of a pivotally mounted latch co-operable with said wheel, said latch having an abutment thereon; a detent automatically movable to position to engage said abutment and retain said latch in in-operative position when the latter is fully disengaged from the latch wheel; and means on said latch between said abutment and the pivot point thereof engaging said detent to retain the latter in in-operative relation to said abutment when the latch is in operative relation with said latch wheel.

3. The combination with a door operating shaft having a latch wheel thereon; of a latch co-operable with said wheel, said latch having an operating arm; and a pivotally mounted detent supported between the arm of said latch and the latch wheel, said

detent being movable, under the influence of gravity, to a position to retain said latch in inoperative position when the latter is moved to fully released position.

4. The combination with a door operating shaft having a latch wheel; of a pivotally mounted gravity controlled latch co-operable with said wheel; and a pivotally mounted detent having a portion thereof slidably engaging said latch, said engaging portion being slidable downwardly on said latch under the influence of gravity, to a position to retain the latter in inoperative position when fully disengaged from the latch wheel.

5. The combination with a horizontally disposed operating shaft having a ratchet wheel thereon; of a vertically movable pivoted pawl member normally influenced under the force of gravity to move to operative position with said ratchet wheel; and a vertically movable pivotally mounted detent engaging said pawl and movable under the influence of gravity, to a position to hold the latter in inoperative position when the same is moved to fully disengaged position from the ratchet wheel.

6. The combination with an operating shaft having a ratchet wheel thereon; of a pivotally mounted pawl member normally gravity-influenced to operative position with said ratchet wheel; a pivotally mounted detent lever cooperable with said pawl member to positively hold the latter in full release position; and means for locking said member and detent in operative position.

7. In a dump car door operating mechanism, the combination with an operating shaft having a ratchet wheel; of a pivoted pawl member cooperable with said ratchet wheel, said pawl member having a handle and a locking shoulder and normally gravity-influenced to operative relation with the ratchet wheel; a pivotally mounted detent lever normally held by said pawl member in elevated position and adapted to fall to a lower position in engagement with said locking shoulder of said member when the latter is moved to release position.

8. In a dump car door operating mechanism, the combination with an operating shaft having a ratchet wheel; of a pivoted pawl member cooperable with said ratchet wheel, said pawl member having a handle and a locking shoulder and normally gravity-influenced to operative relation with the ratchet wheel; a pivotally mounted detent lever normally held by said pawl member in elevated position and adapted to fall to a lower position in engagement with said locking shoulder of said member when the latter is moved to release position; and a locking element cooperable with said pawl member to hold the latter positively in engagement with the ratchet wheel.

9. In a device of the character described, the combination with an operating shaft having a ratchet wheel thereon; of a pivotally mounted pawl member cooperable with said ratchet wheel; a pivotally mounted detent cooperable with said member to hold the latter in inoperative position; and a cover plate extending over said member and detent, said cover plate and member having cooperating opposed portions arranged

to lock said detent lever in inoperative position when said member is in operative position.

In witness that I claim the foregoing I have hereunto subscribed my name this 6th ¹⁵ day of December, 1921.

ARGYLE CAMPBELL.
